(57) **CLAIM**

The ornamental design for a support for a light line generating device, as shown and described.

DESCRIPTION

FIG. 1 is a top perspective view of a support for a light line generating device according to the present invention;

FIG. 2 is a bottom perspective view of the support for a light line generating device shown in FIG. 1;

FIG. 3 is a front view in elevation of the support for a light line generating device shown in FIG. 1;

FIG. 4 is a rear view in elevation of the support for a light line generating device shown in FIG. 1;

FIG. 5 is a left side view in elevation of the support for a light line generating device shown in FIG. 1;

FIG. 6 is a right side view in elevation of the support for a light line generating device shown in FIG. 1;

FIG. 7 is a top view in plan of the support for a light line generating device shown in FIG. 1; and,

FIG. 8 is a bottom view in plan of the support for a light line generating device shown in FIG. 1.

The broken line showing of environmental structure in the figures forms no part of the claimed design.
